United States Patent Office.

JOSIAH S. DICKINSON, OF ESSEX, CONNECTICUT.

Letters Patent No. 76,414, dated April 7, 1868.

IMPROVEMENT IN COMBS.

The Schedule referred to in these Letters Patent and making part of the same.

TO ALL WHOM IT MAY CONCERN:

Be it known that I, JOSIAH S. DICKINSON, of Essex, in the county of Middlesex, and State of Connecticut, have invented certain new and useful Improvements in Combs; and I do hereby declare that the following is a full, clear, and exact description thereof, which will enable others skilled in the art to make and use the same, reference being had to the accompanying drawings forming part of this specification, in which—

Figure 1 is a front view of the comb-holder and comb-plate, shown detached, and with a portion of the comb-holder broken away to exhibit the key-seat.

Figure 2 is a cross-section, showing the comb-plate affixed to the holder.

Similar letters of reference indicate corresponding parts.

This invention consists in the combination of a detachable comb-plate with a holder, whereby the former can be readily removed from the holder when dirty or broken, and a new comb-plate affixed in the said holder instead. The holder consists of the plate A, and may be constructed in any suitable design or ornamental configuration, as that shown. The comb-plate B is toothed in one direction only, and the back, A, thereof fits in the groove *a* of the holder, as shown. The comb-plate is held in the holder by means of key-pins *b*, which fit in key-seats or slots, one-half of which are formed in the holder, and one-half in the comb-plate, as shown, whereby the comb-plate is withdrawn laterally in the form of the invention shown in the drawings, but I contemplate making the two parts in such a manner that the groove may be dispensed with. For example, the comb-plate will be held against a shoulder near the lower edge of the holder by screws or other means.

In practice, the combs will be made generally of iron, but the holder can be struck in sheet metal, or made of hard rubber, wood, ivory, bone, or other suitable material. The comb-plates may be affixed to the holder in other ways than that shown, as, for example, screws or spring-catches may be employed, but I have set forth what I consider to be the best means of holding the comb-plate in place, as the plate *c* of the key covers the ends of the grooves, and presents a finished and ornamental appearance.

The advantages of this invention are as follows: First, the comb-plates may be made of small pieces, and more ivory (which latter is growing scarcer every year) utilized to accomplish the same result, for many pieces are too small for the double combs as heretofore made. Second, the combs are more conveniently held and used by means of the holder plate. Third, a set of several comb-plates may be furnished with each holder, which will enable a new one to be set at any time.

Having thus described my invention, I claim as new, and desire to secure by Letters Patent—

As a new article of manufacture, a comb-holder A, constructed substantially as described.

The above specification of my invention signed by me, this 14th day of February, 1868.

JOSIAH S. DICKINSON.
